CLOTH SPREADING MACHINE

Nathan Obedin, 2001 E. 9th St., Brooklyn, N.Y.

Filed July 17, 1959, Ser. No. 56,819

Term of patent 14 years

(Cl. D55—1)

FIG.1

FIG.2

FIG. 3

FIGURE 1 is a front perspective view of a cloth spreading machine embodying my new design,

FIGURE 2 is a side elevational view of the end opposite that shown in FIGURE 1; and

FIGURE 3 is a perspective view thereof taken from the rear and top.

I claim:

The ornamental design for a cloth spreading machine, substantially as shown.
